UNITED STATES PATENT OFFICE.

JOHN KERWIN, OF DETROIT, MICHIGAN.

BLACKSMITH'S FORGE.

SPECIFICATION forming part of Letters Patent No. 549,605, dated November 12, 1895.

Application filed December 31, 1894. Serial No. 533,375. (No model.)

To all whom it may concern:

Be it known that I, JOHN KERWIN, a citizen of the United States, residing at Detroit, county of Wayne, State of Michigan, have 5 invented a certain new and useful Improvement in Blacksmiths' Forges; and I declare the following to be a full, clear, and exact description of the invention, such as will enable others skilled in the art to which it appertains to make and use the same, reference being had to the accompanying drawings, which form a part of this specification.

My invention relates to new and useful improvements in a blacksmith's forge, having 15 for its object greater simplicity, efficiency, and economy than have heretofore been found in devices of this class.

My invention consists of the construction, combination, and arrangement of devices 20 hereinafter described and claimed, and illustrated in the accompanying drawings, in which—

Figure 1 is a view in perspective illustrating 25 my invention. Fig. 2 is a plan view of the same. Fig. 3 is a vertical section on the line 3 3, Fig. 2. Fig. 4 is an inverted plan view showing parts in section. Fig. 5 is a detail view in cross-section on the line 5 5, Fig. 3. Fig. 6 is a detail view illustrating the 30 manner of fulcruming the operating-lever.

My invention has special reference as one of its chief features to the construction of the bellows.

In the drawings, A represents a metallic 35 shell or case, preferably made of sheet metal, of tubular form. This case forms the side inclosure of the bellows and is extended therebeneath to constitute, also, a support for the device, the case being projected, also, above 40 the bellows to support the air-tube and bed hereinafter described. While the case A forms the surrounding side wall of the bellows, I engage therewithin, toward the lower end of the case, a movable head B, having a 45 flexible engagement at its periphery with the inner periphery of the case adjacent thereto, as by means of an intervening suitable flexible fabric B'. To engage said fabric with the case, I prefer to employ an inner hoop B², 50 clamping the outer edge of the fabric B' between it and the inner face of the case, the hoop B² preferably being bolted to the case,

as indicated at b. The inner edge of the fabric B' may be similarly engaged to the periphery of the head B, as by means of a hoop B³, 55 clamping the inner edge of the fabric between it and the head, the hoop B³ being bolted to the head. The head B is provided with a suitable valve B⁴.

C denotes a head, forming the top of the 60 bellows, the same being flexibly engaged with the inner face of the case A, as by means of a suitable fabric C'. This fabric C' may be united to the case A by means of a hoop C², clamping the fabric between it and the case, 65 the hoop C² being bolted to the case, as shown at c. The inner edge of the fabric C' may be united to the periphery of the head C in the same manner as the fabric B' is engaged to its head, as by means of a clamping-hook C³. 70

Between the heads B and C, I locate a diaphragm D, which may be supported upon an inner hoop D², bolted to the case A. This diaphragm D is provided with a valve D'.

The head C is preferably weighted, as by 75 weight C⁴, of any desired heft.

E denotes the bed-plate of the forge, forming a cover over the case A, but spaced therefrom to allow a free circulation of air thereunder, said bed-plate being preferably supported upon the case A by means of intervening brackets A'. The bed-plate E is depressed at the center, as indicated at E', and is provided with an orifice e therethrough. 80

With the lower head B of the bellows is 85 engaged a lever F, connected at one extremity, as by a rod F', to an operating-lever or bar F², fulcrumed in any desired manner, as at f, upon a standard F³, supported upon the bed-plate E.

The lever F is preferably bifurcated at the end opposite the rod F', the two forks F⁴ and F⁵ being fulcrumed at their outer extremities upon a bracket G, engaged upon the case A, f' indicating the point of fulcrum. 90

The case A is constructed with vertically-elongated slots a to permit the movement of the forks F⁴ F⁵. Said forks are engaged with the head B by means of intervening brackets H H. 100

Between the head C and the diaphragm D is formed the inflating-chamber C⁵ of the bellows, the head C being shown in its inflated position in dotted lines, Fig. 3. It will be

apparent that on manipulating the lever F^2 air will be forced into the chamber J between the lower head B and the diaphragm D , the air passing from the chamber J into the chamber C^5 through the valve D' , said latter valve preventing the escape of air from the chamber C^5 therethrough.

Communicating with the chamber C^5 of the bellows is a pipe K .

- 10 L is a pipe supported at its extremities near the upper end of the case A . One end of the pipe L is connected with the pipe K , as by an elbow K' , so that air will pass from the chamber C^5 into the pipe L . The pipe L is constructed with an opening l therein, registering with the opening e in the bed-plate E , and through which air is forced to the fire in the hearth or depressed portion E' of the bed-plate E . I design to have the plate E to rest air-tight over the pipe L , and for this purpose I construct the bed-plate E with an arc-shaped bearing E^2 , forming a concaved seat upon the pipe L , a suitable packing, as indicated at $l' l$, preferably intervening between the pipe L and the bearing E^2 . I design, also, that the left of the plate E shall rest almost or quite entirely upon the pipe L , the brackets A' being so adjusted as simply to steady the bed-plate and hold it firmly in position. The left of the plate E will thus tend to insure an air-tight joint of its bearing E^2 upon the pipe L .

It will be specially noticed that the bed-plate E is spaced from the case A to allow a free circulation of air under the bed-plate. This bed-plate is supported centrally upon the transverse pipe L , and near its periphery it rests upon the brackets A' , leaving a free air-space all around between the top of the case A and the bed-plate to allow a free circulation of air. Where the shell is continuous to the top and about the bed of the forge, the shell is inevitably heated to a great extent, in consequence of which the leather or flexible connection of the bellows soon cracks, the heat quickly destroying the leather or analogous fabric, rendering it necessary to often repair the forge and provide new leather. This is the great practical difficulty in forges of this nature heretofore constructed, and my invention is especially intended to overcome this difficulty.

The pipe L at its free end I provide with a removable cap L' . It will be apparent that when ashes fall through the orifice e into the pipe L they may be readily blown out by removing the cap L' and operating the bellows. In the ordinary use of the forge the cap L' will be located in place. To keep a fire on the forge, however, when the bellows is not in operation, the cap L' may be removed, thereby admitting a draft of air through the adjacent end of the pipe L to the fire to keep the fire alive.

I prefer to locate in the orifice e a spreader e' , of any suitable construction, which may conveniently be supported in position by

screwing its lower end into the lower portion of the pipe L .

I prefer to engage the lever F^2 with the standard F^3 , as more particularly shown in Fig. 6, the view in Fig. 6 being from a point opposite that shown in Fig. 3. To this end I prefer to curve the standard F^3 , as indicated in Fig. 6, and to form in its outer end a socket f^2 to receive the round head of a bolt f^3 , by which the lever F^2 is engaged with the standard F^3 .

M denotes a hood located upon the bed-plate E to carry the products of combustion to an uptake M' .

N denotes a coal-box.

It will be seen that the device as so constructed is portable, easily operated, as well as efficient in its operation, and that should either of the flexible fabrics $B' C'$ become worn out they can readily be renewed by detaching the bolts by which they are engaged in place with the corresponding head and with the case A .

The device will now be understood.

It is to be observed that as so constructed the flexible fabrics, which may be made of leather or of other suitable material $B' C'$, are never creased, either in their location or operation. In the movement of the corresponding heads $B C$ the corresponding fabrics $B' C'$ move from their inner edges upward and downward, said fabrics swinging on their outer edges, which are united to the case A . By this construction with fabrics of, say, five inches in width I am enabled to get as good results as are ordinarily obtained in the use of, say, ten inches of fabric, as bellows are ordinarily constructed, while by attaching the fabrics at their outer edges directly to the case I get my bellows the full diameter of the case without any lost space thereabout.

By locating the bracket G outside the case A , as shown, I am enabled to remove the fulcrumed points of the forks $F^4 F^5$ from the pivotal connection of said forks with the brackets $H H$, as at $h h$, by which means I shorten the necessary vertical movement of the forward end of the lever F and a corresponding slot a' . This enables me to locate the head B lower than would otherwise be required and to make the forge of just the required height.

While I have described and entitled my invention as a "blacksmith's forge," since it is especially well adapted for a blacksmith's use, yet I would have it understood that I contemplate as coming within the scope of my invention any use for which it may be found adapted, since a portable blast-forge of this description may evidently be used for a variety of purposes, all of which I contemplate as embodied in my invention herein set forth.

In Fig. 3 I have shown a modification in which the elbow K' is provided with a valve and with a steam-pipe K^2 leading into the pipe L , by which means, if it should be de-

sired, the device may be used as a steam-forge simply by closing the valve K³ in said elbow and letting the steam into the pipe L through the pipe K². The pipe K² is also 5 provided with a valve K⁴ to govern the admission of steam therethrough.

What I claim as my invention is—

1. In a forge, the case, the bellows located therein, and the air pipe connected to the bellows at its lower end, and extending across through the case at its upper end, combined with the bed plate mounted above the top of the case and supported at its center upon the air pipe; there being a space between the top 10 of the case and the bottom of the bed plate for the free circulation of air, substantially as described.
2. In a forge, the bellows located in the case, and the air pipe connected to the bellows at its lower end, and having its upper end extending through the top of the case and forming a support for the center of the bed plate, combined with the case, and the 15

- 25
- 30
- 35
- 40

bed plate raised above the case and having its central bottom portion grooved so as to fit over the slotted portion of the pipe; a space being left all around between the top of the case and the under side of the bed plate for the free circulation of air, substantially as set forth.

3. In a forge, the case, provided with slots, the bracket secured to the case at or near the slots, and the pronged lever having its ends projecting through the slots and connected to the under side of the bellows, combined with the bellows, the connecting rod, the hand lever, the support for the lever, and the headed bolt which extends through both the support and the lever, substantially as specified.

In testimony whereof I sign this specification in the presence of two witnesses.

JOHN KERWIN.
